[57] CLAIM

The ornamental design for a bottle carrier, as shown and described.

DESCRIPTION

FIG. 1 is a bottom perspective view of a bottle carrier
showing my new design;
FIG. 2 is a top plan view;
FIG. 3 is a bottom plan view; and
FIG. 4 is a side elevational view thereof, the other three sides being the same in appearance.
